UNITED STATES PATENT OFFICE.

MARCUS H. MOFFETT, OF LAKEWOOD, OHIO, ASSIGNOR TO NATIONAL CARBON COMPANY, OF CLEVELAND, OHIO, A CORPORATION OF NEW JERSEY.

ELECTRODE FOR PROJECTION APPARATUS.

1,165,619.

Specification of Letters Patent.

Patented Dec. 28, 1915.

Application filed October 1, 1913. Serial No. 732,704.

To all whom it may concern:

Be it known that I, MARCUS H. MOFFETT, a citizen of the United States, residing at Lakewood, in the county of Cuyahoga and State of Ohio, have invented a certain new and useful Improvement in Electrodes for Projection Apparatus, of which the following is a full, clear, and exact description.

This invention relates to an improvement in electrodes for use in projection apparatus.

The invention is intended primarily to be applied to carbon electrodes for small and inexpensive projection lamps such as are used quite extensively in schools, fraternal societies and in the home. This type of projection lamp has no means for feeding the carbons together, the operation being performed by grasping the outer ends of the carbons in the hands and simultaneously pushing them inward through the holder until the desired length of arc is obtained. Since the drop around the arc is considerable, it is obvious that the operator would receive an annoying shock each time the adjustment is made unless insulating gloves are worn. Gloves are cumbersome and inconvenient and I have made my improvement with the idea of eliminating their use.

One object of my invention is therefore to secure a cheap and convenient insulation for the end of the electrodes.

Another object is to provide means on the end of the electrodes to break the circuit before they are pushed so far within the holder that they cannot be withdrawn from the outside of the lamp.

In the drawings, Figure 1 is a top view of a projection apparatus with my invention applied thereto. Fig. 2 is an enlarged cross section of one of the electrode holders with the electrode in the cutout position. Fig. 3 is an enlarged end view of the electrode holder with part removed to show the contact and gripping arrangement.

In the drawing, 1 is the main casing of the apparatus containing the condensing arrangement and 2 is the usual adjustable projection part of the apparatus. The electrodes 3 and 4 usually consisting of cored carbons passed through insulating bushings 5 and 6 which have means, such as a spring 7 and a V shaped metallic part 8, for making the electrical connection and holding the electrodes in their adjusted positions. Binding posts 9 pass through the bushings 5 and 6 and are

secured to the V shaped members 8. The terminal wires are fastened to the binding posts 9 in the usual way (not shown).

My invention relates to an adherent insulating coating 10 applied to the ends of the electrode. The insulating coating which has been found most satisfactory, due to the simplicity of its application, is water glass, or sodium silicate. This may be applied by dipping one end of each electrode a short distance in a water glass solution. Upon drying, a good and very adherent insulating coating is formed which the operator may grasp for adjusting the electrodes without receiving a shock. It will be evident that other hardening insulating substances such as pitch or asphalt may be used, but I have found water glass to be preferable.

With the usual type of electrode, it frequently happens that the operator will accidentally push it so far in the bushing or holder that it cannot be withdrawn or further adjusted without extinguishing the arc and opening up the apparatus to push it back with a pencil or other instrument.

This frequently happens when the carbons are almost consumed and the operator thinks that they can be adjusted a slight additional extent before being removed. Whenever the electrodes are thus adjusted so far in the bushing that they cannot be withdrawn from the outside, it is annoying to the operator as well as to the spectators to have the lamp shut down for a minute or two until the electrodes can be pushed out so that new ones can be inserted. My invention is designed to prevent this annoyance.

The insulating coating is of sufficient length to pass under the contact spring and break the contact while the electrode end still projects from the bushing a sufficient distance to be readily grasped by the operator. It will thus be seen that the circuit will be interrupted and the arc extinguished before the electrode has been consumed to a point where it may accidentally be pushed into the bushing beyond the grasp of the operator.

As soon as the arc is extinguished, the remaining electrode, or electrodes, can be removed and new ones inserted so that the operation of the lamp is only interrupted for a second or two.

The thickness of the insulating coating on the electrodes may vary but it should preferably be of no appreciable thickness so that

the electrodes can be properly packed and shipped. The length of the bushing of course may be varied, but with the usual type of lamp, it will be found that an inch or an inch and a half will be the proper length to furnish a convenient insulation for the safety of the operator as well as the automatic cut-out previously described.

Having described my invention, what I claim is:

1. An electrode for projection apparatus having an adhering coating of an insulating substance on one end.
2. An electrode for projection apparatus having a coating of water glass on one end,

Copies of this patent may be obtained for five cents each, by addressing the "Commissioner of Patents, Washington, D. C."

the remaining surface of the electrode being conducting.

3. In projection apparatus the combination of the holder with a contact device and an electrode having a coating of an insulating substance on one end adapted to pass under said contact device to interrupt the circuit before the electrodes are completely adjusted within said holder.

In testimony whereof, I hereunto affix my signature.

MARCUS H. MOFFETT.
